[57] CLAIM

We claim the ornamental design for the security switch, as shown and described.

DESCRIPTION

FIG. 1 is a front and right perspective view of the new ornamental security switch of the present invention.

FIG. 2 is a right side view thereof, where the left side view, not shown, is identical.

FIG. 3 is a top view thereof.

FIG. 4 is a bottom view thereof; and,

FIG. 5 is a front view thereof, where the rear view, not shown, is identical.
